Attorney

UNITED STATES PATENT OFFICE.

CHARLES GAMER, OF FORT WORTH, TEXAS.

GAS PRODUCER.

1,409,440.

Specification of Letters Patent. Patented Mar. 14, 1922.

Application filed December 18, 1920. Serial No. 431,535.

To all whom it may concern:

Be it known that I, CHARLES GAMER, a citizen of the United States of America, residing at Fort Worth, in the county of Tarrant 5 and State of Texas, have invented certain new and useful Improvements in Gas Producers, of which the following is a specification.

My invention relates to apparatus for producing gas and particularly to apparatus for producing gas from coal and lignite and other low grades of coal, and the object is to provide simple apparatus which can be manufactured at small cost and which will be 10 highly efficient in making gas for use by individual enterprises and which can be used for driving small motors, thus making it possible for a small factory to manufacture gas for its own use. Another object is to provide 15 apparatus in units which can be increased to make gas for a city or several manufacturing enterprises or machine shops. Other objects and advantages will be fully explained in the following description and 20 the invention will be more particularly pointed out in the claims.

Reference is had to the accompanying drawings which form a part of this application.

Fig. 1 is a vertical section of a gas manufacturing plant. Fig. 2 is a detail plan view of the support for the rotating chute. Fig. 3 is a plan view of the grate cleaning apparatus. Fig. 4 illustrates how a number of 25 units may be operated with one system of gearing.

Similar characters of reference are used to indicate the same parts throughout the several views.

In carrying out the objects of this invention, a furnace 1 is provided and supported on a base 2 which may serve as an ash box. The furnace 1 is provided with a stationary grate 3. Means are provided for feeding 30 coal or lignite to the furnace. A rotatable chute 4 is centrally positioned in the furnace casing 1 and a gear wheel 5 is made rigid with the chute 4. A hopper 6 is mounted on the furnace casing 1. A rotatable valve or 35 stoker 7 is mounted in the lower part of the hopper 6. An opening in the top part of the casing completes the passage from the hopper to the chute 4. Means are provided for revolving the stoker 7 and the chute 4. A shaft 8 journaled in suitable hanging 40 bearings 9 carries a bevel gear 10. The shaft 45

8 may be driven by any suitable power. The gear wheel 10 drives bevel gear 11 which drives a shaft 12. The shaft 12 carries rigid therewith a bevel gear 13 and the gear 13 50 drives a bevel gear 14 which drives the stoker valve 7. A vertical shaft 15 is provided with a bevel wheel 16 which meshes with and drives a gear wheel 17 which is rigid with a shaft 18. The shaft 18 carries 55 a bevel wheel 19 rigid therewith. The bevel wheel 19 drives the wheel 5 which is rigid with the chute 4. The gear wheel 10 drives the gear wheel 16. The gear wheel 5 is supported loosely on a circular flange 21 which 60 may be cast on the interior of the casing 1.

The grate cleaning apparatus is also operated by the vertical shaft 15. Scrapers 22 are dragged over the grate 3. The scrapers 22 are provided with lugs 23 at each corner 65 and sprocket chains 24 are driven by sprocket wheels 25, 25, 25, and 26. The sprocket wheel 26 has bevel face cogs 27 which mesh with a bevel wheel 28 which is rigid with the shaft 15. The wheel 28 drives the 70 sprocket wheel 26 and all the other sprocket wheels are driven from the wheel 26. The sprocket wheels drive the chains 24 and so move the scrapers 22 over the grate 3. The scrapers 22 are perforated so that they will 75 not be heated to melting point. The perforations permit air to pass up through the grate 3 and through the scrapers and prevent the scrapers from becoming too hot. The scrapers keep the grate clear of ashes so 80 that plenty of air for combustion purposes will pass through the grate. The openings in the casing for the passage of the chains 24 and scrapers 22 are sufficiently large to permit the inflow of all the air that is necessary for 85 combustion. The ashes fall down in the ash box 2 and may be removed through the door 29. The gearing is so arranged that the scrapers 22 move very slowly. The chute 4 is rotated constantly and this chute carries 90 fingers 30 which serve as leveling means to prevent the coal from projecting up past the bottom of the chute 4. The rim 21 will support the chute 4 in its normal working position, but the coal lying on the grate 3 will 95 100 also tend to support the chute 4 and thus lessen the friction on the rim 21. The chute 4 will conduct the coal to the point of combustion so that the coal will not interfere with the products of combustion rising in 105 the form of gas within the furnace or casing 1. The gas escapes through an outlet pipe 31

to the scrubbing means which consists of two units 32 and 33. Each unit has a series of horizontal baffle plates 34 and 35. The plates 34 have openings in the central parts 5 and the plates 35 do not extend entirely to the walls of the casing units 32 and 33 so that the gas in passing downwardly in the unit 32 must take a zig zag course and finally pass out through the outlet pipe 36 to the 10 unit 33 where the gas takes a similar course upwardly in the unit 33. The gas may be taken from the unit 33 by a service pipe 37. The plates 34 and 35 are supported by frame members 38. The impurities pass down a 15 pipe 39 into the water box 40 and the pipe 40 projects below the surface of the water or liquid in the box 40. The overflow from the box 40 passes through an opening 41 into the ash box 2 and will moisten the products 20 therein. By the time the gas leaves the two purifying units 32 and 33, it will be ready for use for lighting, heating, and for power purposes.

What I claim, is,—

25 1. A gas producer comprising a receptacle for the combustion of gas producing material, a rotatable chute suspended in said receptacle for delivering the material to the lower part of said receptacle, stoker mechanism for feeding material to said chute, and means for actuating said stoker mechanism and simultaneously rotating said chute.

30 2. A gas producer comprising a receptacle for the combustion of gas producing material, a rotatable chute suspended in said receptacle for delivering material to the lower part of said receptacle, stoker mechanism for feeding material to said chute, means 35 carried by said chute for spreading the gas producing material, and means for actuating said stoker mechanism and simultaneously rotating said chute.

3. A gas producer comprising a receptacle 45 for the combustion of gas producing material, a rotatable chute suspended in said receptacle for delivering the material to the lower part of said receptacle, stoker mechanism for feeding the material to said chute, a grate for said receptacle, and scrapers moving over said grate for clearing the grate and for causing the passage of air to said receptacle.

4. A gas producer comprising a receptacle 50 for the combustion of gas making material, a rotatable chute suspended in said receptacle for delivering the material to the lower part of said receptacle, means for feeding the material to said chute, a grate for said receptacle, scrapers for cleaning said grate 55 and for opening passage ways for air to said receptacle, and means for moving said scrapers slowly across said grate.

5. In a furnace for the combustion of gas 60 making material provided with an ash box and provided with an outlet for the products of combustion, a rotatable chute suspended in said furnace, stoker mechanism for feeding the material to said chute, a 65 grate and perforated scrapers for cleaning said grate and for providing passage ways for air to said furnace, gearing for moving said scrapers, and means for simultaneously actuating said stoker mechanism, rotating said chute and for driving said gearing.

6. In a furnace for the combustion of gas 70 making material provided with a grate, perforated scrapers for cleaning said grate and for providing passage ways for air to said furnace, and gearing for slowly but constantly moving said scrapers across said 75 grate.

In testimony whereof, I set my hand, this 14th day of December, 1920.

CHARLES GAMER.
